UNITED STATES PATENT OFFICE.

HERBERT J. BUCHSBAUM, OF CHICAGO, ILLINOIS.

LOCKET.

Application filed February 21, 1921. Serial No. 446,931.

To all whom it may concern:

Be it known that I, HERBERT J. BUCHSBAUM, a citizen of the United States, residing at Chicago, in the county of Cook and State of Illinois, have invented a certain new and useful Improvement in Lockets, of which the following is a full, clear, concise, and exact description, reference being had to the accompanying drawings, forming a part of this specification.

This invention relates to lockets and more particularly to a locket having means at opposite ends thereof for securing the same on a band, or other flexible member.

It is a purpose of this invention to provide a locket comprising a box-like member having an open side provided with means at opposite ends thereof for securing the same on a band or other flexible member, said box-like member being provided with a pair of pivoted superposed leaves hinged thereto adapted to be moved into position to close the open side of said box-like member, both sides of said leaves being adapted to receive illustrations, insignia, or other ornamentation thereon.

It is a further purpose of the invention to provide a locket comprising a body member having a rear plate, provided with side flanges in which a pair of clamping levers are pivotally mounted at the opposite ends thereof, said clamping members being adapted to be turned to such a position that a band or other flexible supporting member be passed through said locket between the same and said rear plate when in one position and being adapted to clamp said flexible member between the same and said rear plate when in another position.

It is still a further purpose of the invention to provide a locket of the above character with angular clamping levers having overlapping portions by means of which they are moved into and out of clamping positions, said operating portions being in the form of leaves adapted to fit between the side flanges of said rear plate and extending substantially at right angles to the gripping portions of said levers, whereby a box-like member is formed when the clamping levers are in clamping position, the top of which is opened upon moving said clamping levers to unclamping position.

Other objects and advantages of the invention will appear as the description of

the accompanying drawings showing one form that my invention may take, proceeds. However, I desire to have it distinctly understood that I do not intend to limit myself to the exact details shown or described in the specification, but that I intend to include as part of my invention all such obvious changes and modifications as would occur to a person skilled in this art and as would fall within the scope of the claims.

In the drawings:

Fig. 1 is a top plan view of the locket showing the same applied to a flexible supporting band,

Fig. 2 is a side elevation thereof,

Fig. 3 is a section taken on line 3—3 of Fig. 2, showing the locket in open position in dotted lines,

Fig. 4 is a section taken on the line 4—4, Fig. 3.

Referring in detail to the drawings the improved locket, which is commercially known as a "Waldemar," is shown as being mounted on a flexible member 5 and comprises a base plate 6 having the side flanges 7 and 8 extending upwardly therefrom substantially at right angles thereto. In the drawings the flexible supporting member 5 is shown as comprising a pair of bands or strips, but a single band or any other flexible supporting device can be used for the locket. The flanges 7 and 8 are provided with suitable openings through which extend the pivot members 9 and 9' of the leaves 10 and 11 thus securing the same to the base member pivotally between the side flanges thereof. These pivot members may be either integral with the leaves 10 and 11 or may be separate pivot pins as desired.

The members 10 and 11 are provided with substantially right angularly extending end portions 12 and 13 and the clamping members having arms that extend substantially at right angles to each other that are thus formed are suitably strengthened at the angle thereof as at 13, 13', the enlarged portion being adapted to receive a separate pivot pin if desired. It will be seen that the right angular end portion 13 is longer than the end portion 12 and that the pivot 9' is spaced a greater distance from the base plate 6 than the pivot 9 whereby the members 10 and 11 are adapted to fit over each other as shown in Figs. 3 and 4, and the member 11 is adapted to be moved so as to be flush with the top edges of the flanges 7 and 8 when

in the position shown in Figs. 3 and 4 in full lines, thus forming a substantially rectangular box-like member that provides a space 14 in the same. The distance between 5 the flanges 7 and 8 is slightly less than the width of the member 11, thus when the member 10 has been swung into the position shown in full lines in Fig. 3 and the member 11 is swung into the full line position in 10 Fig. 3, the member 11 will be held in this position due to the tight fit between the same and the side flanges 7 and 8 the members 7 and 8 being slightly sprung laterally when the member 11 is forced between them 15 into the position shown in Fig. 4 and the member 11 will hold the member 10 in this position. When the members 10 and 11 are in the dotted position shown in Fig. 4 the locket will be open and the same will be free 20 to slide along the flexible member 5. In order to clamp the locket in position on the flexible member the member 10 is first moved from the dotted to the full line position in Fig. 3, thus clamping the locket to 25 the flexible member at one end thereof and then the member 11 is moved from the dotted to the full line position, thus clamping the other end of the locket to the band 5 and holding the member 10 in clamping position. 30 The members 10 and 11 are preferably ornamented in any desired manner, any suitable illustrations being placed on the opposite faces of each of these members. It will thus be seen that a locket is provided 35 that has a pair of leaves pivoted to the base member thereof which are ornamented on their opposite faces, and which are adapted to be turned so as to be in overlapping position, and that this locket is provided with 40 means for securing the same to a flexible supporting member at the opposite end thereof, said means being preferably in the form of clamps one arm of each of the clamps forming the leaves that are pivoted 45 between the base member flanges.

Having thus described my invention what I claim and desire to secure by U. S. Letters Patent is:

1. A locket having a base plate, a pair of 50 leaves each having smooth unbroken surfaces adapted to receive ornamentations thereon, means for pivotally mounting said leaves on said base plate at opposite ends thereof, said leaves being adapted to be folded into superposed parallel relationship and being substantially co-extensive, and means for attaching a flexible supporting member to said locket at the opposite ends of said base plate.
2. A locket having a base plate, a pair of 60 leaves each having smooth unbroken surfaces adapted to receive ornamentations thereon, and means for pivotally mounting said leaves on said base plate at opposite ends thereof, said leaves being adapted to be

folded into superposed parallel relationship and being substantially co-extensive, said leaves having right-angular extensions co-operating with said base plate to clamp a flexible supporting member to said locket 70 at opposite ends of said base plate.

3. A locket having a base plate, a pair of leaves each having smooth unbroken surfaces adapted to receive ornamentations thereon, and means for pivotally mounting 75 said leaves on said base plate at opposite ends thereof, said leaves being adapted to be folded into superposed parallel relationship and being substantially coextensive, said leaves having right-angular extensions co-operating with said base plate to clamp a flexible supporting member to said locket 80 at opposite ends of said base plate, said leaves and base plate together forming a closed box-like member when said extensions are in clamping position.

4. A locket having a flat base plate providing a closed rear wall therefor, said base plate having right-angularly extending side flanges forming closed side walls for said locket, and a pair of smooth, flat overlapping leaves forming a closed front for said locket and having right-angular extensions closing the ends of said locket to form a closed rectangular box-like locket member, one of 90 said leaves holding the other of said leaves in closed position.

5. A locket of the character described comprising a base member having side flanges, and a pair of clamping members 100 pivotally mounted between said side flanges, said locket being adapted to receive a flexible supporting member, said clamping members each comprising an operating handle and a gripping member extending at an 105 angle thereto, said handles extending toward each other when in clamping position, one of said gripping members being longer than the other thereof, whereby said handle portions lie in overlapped position 110 with the upper one thereof flush with the top edge of said side flanges and said gripping members closing the ends of said locket when said clamping members are in clamping position.

6. A locket of the character described comprising a base member having side flanges, and a pair of clamping members 115 pivotally mounted between said side flanges, said locket being adapted to receive a flexible supporting member, said clamping members each comprising an operating handle and a gripping member extending at an angle thereto, said handles extending toward each other when in clamping position, one 120 of said gripping members being longer than the other thereof, whereby said handle portions lie in overlapped position with the upper one thereof flush with the top edge of said side flanges, the upper of said handle 125

portions fitting snugly between said side flanges to hold both said clamping members in clamping position.

7. A locket having a base plate providing a closed rear wall therefor, said base plate having side flanges forming closed side walls for said locket, and a pair of overlapping leaves forming a closed front for said locket and having angular extensions closing the ends of said locket to form a closed locket member.

8. A locket having a base plate providing a closed rear wall therefor, said base plate having side flanges extending perpendicular

thereto and forming closed side walls for 15 said locket, and a pair of overlapping leaves forming a closed front for said locket and having right-angular extensions closing the ends of said locket to form a closed rectangular locket member, said angular extensions adapted to engage a flexible supporting member and clamping said member between said base plate and said extensions.

In witness whereof, I hereunto subscribe my name this 1st day of February A. D., 25 1921.

HERBERT J. BUCHSBAUM.
